(57) **CLAIM**

The ornamental design for a rope cinch device as shown and described.

DESCRIPTION

FIG. 1 is a perspective view of a rope cinch device showing the new design in a closed position with a rope inserted into it.

FIG. 2 is a perspective view of a rope cinch device showing the new design in an open position.

FIG. 3 is a perspective view of a rope cinch device showing the new design in a closed position.

FIG. 4 is a top view of a rope cinch device showing the new design.

FIG. 5 is a bottom view of a rope cinch device showing the new design.

FIG. 6 is a first side view of a rope cinch device showing the new design in an open position.

FIG. 7 is a second side view of a rope cinch device showing the new design in an open position.

FIG. 8 is a first side view of a rope cinch device showing the new design in a closed position.

FIG. 9 is a second side view of a rope cinch device showing the new design in a closed position.

FIG. 10 is a first section view of a rope cinch device showing the new design taken at the line shown in FIG. 6.

FIG. 11 is a second section view of a rope cinch device showing the new design taken at the line shown in FIG. 6; and,

FIG. 12 is a third section view of a rope cinch device showing the new design taken at the line shown in FIG. 6. The broken lines are to show environmental structure only and form no part of the claimed design.

1 Claim, 4 Drawing Sheets
